UNITED STATES PATENT OFFICE.

JUDSON L. MOTT, OF ADRIAN, MICHIGAN, ASSIGNOR TO MERCHANTS ADVERTISING COMPANY, OF ADRIAN, MICHIGAN, A PARTNERSHIP COMPOSED OF JUDSON L. MOTT AND JOHN E. MOTT.

DESIGN FOR A CLOCK CASE.

Application filed September 28, 1928. Serial No. 28,820. Term of patent 14 years.

To all whom it may concern:

Be it known that I, JUDSON L. MOTT, a citizen of the United States, and resident of Adrian, county of Lenawee, State of Michigan, have invented a new, original, and ornamental Design for a Clock Case, of which the following is a specification, reference being had to the accompanying drawing, forming part hereof.

The figure is a perspective view of a clock case showing my new design.

I claim:

The ornamental design for a clock case, as shown.

In testimony whereof I have hereunto signed my name to this specification.

JUDSON L. MOTT.
